UNITED STATES PATENT OFFICE.

ELMER H. CROSS, OF TOLEDO, OHIO.

DESIGN FOR AN AIR-CELL FORMATION OF AN AUTOMOBILE-RADIATOR FRONT.

59,457.

Specification for Design.

Patented Oct. 25, 1921.

Application filed March 26, 1920. Serial No. 369,104. Term of patent 3½ years.

To all whom it may concern:

Be it known that I, ELMER H. Cross, a citizen of the United States, residing at Toledo, in the county of Lucas and State of Ohio, have invented a new, original, and ornamental Design for an Air-Cell Formation of an Automobile-Radiator Front, of which the following is a specification, reference being had to the accompanying drawing, forming a part thereof.

The drawing is a fragmentary view of a portion of a radiator front of my new design.

I claim:

The ornamental design for an air cell formation of an automobile radiator front, substantially as shown.

ELMER H. CROSS.
